UNITED STATES PATENT OFFICE.

JOHN JOSEPH KINNEY, OF AUBURN, NEW YORK, ASSIGNOR TO COLUMBIAN ROPE COMPANY, OF AUBURN, NEW YORK, A CORPORATION OF NEW YORK.

SPINNING-JENNY NIPPER.

Application filed September 1, 1922. Serial No. 535,776.

To all whom it may concern:

Be it known that I, JOHN JOSEPH KINNEY, a citizen of the United States, residing at Auburn, in the county of Cayuga and State 5 of New York, have invented certain new and useful Improvements in Spinning-Jenny Nippers; and I do hereby declare the following to be a full, clear, and exact description of the same, reference being had to the accompanying drawings, forming part of this 10 specification.

This invention relates to nippers for spinning jennies, the object being to provide a competent means for feeding a central member, such as a marker or thread, in suchwise 15 that the fiber will be spun around the same in a uniform layer whereby the central member will be completely enclosed and occupy a uniform position in the yarn throughout 20 its length.

While the invention is primarily designed to insert an identifying marker such as tape, paper or thread within a yarn which is subsequently employed in the manufacture 25 of rope whereby certain advantages are secured over the customary practice of inserting the marker between the yarns or between the strands of the rope, it is not limited to such use as it may with advantage 30 be employed to insert centers of one kind of fiber in yarns or single strand cords, the outside of which is made of a different fiber, or the center may be colored differently from the outside.

The type of nipper adopted for illustrating the present invention employs the customary bell, grooved jaws yieldingly held together for smoothing up the yarn and upper and lower nipper steels also yieldingly 35 held together for spreading the fiber and determining the point where the initial twist shall be imparted to the yarn. In accordance with the present invention the center member of the yarn is fed in through 40 a suitable guideway at the point where the fiber is spread by the steels and the initial twist commences with the result that the laterally spread fiber wraps around and completely encloses the center in a uniform 45 layer.

In the drawings,—

Figure 1 is a front view of the nipper.

Fig. 2 is a side elevation partly broken away and in section looking at the right 55 hand side of Figure 1.

Fig. 3 is a top plan with the upper jaw and upper steel both removed.

Fig. 4 is a bottom plan of the upper nipper steel.

Fig. 5 is an elevation looking at the entrance side or rear of the upper steel.

The nipper body 10 is of the usual construction having an extended base 11, a threaded lug 12 for a steel adjusting screw 53 and an extension 14 to receive the set 60 screw 15 which holds the bell and tube in place with its cavity in registry with the slot 65 at the top of the support.

The bell 20 is preferably integral with the tube 21 having a triangular vertical slot to 70 receive the two nipper steels and having a rectangular horizontal slot to receive the two nipper jaws 23 and 24 which are held in place between the steels and a split retaining ring 25 secured to the front of the 75 tube by the screws 26 or similar fastenings.

As is customary in the art the upper jaw member 23 is yieldingly held in engagement with the lower jaw member 24 by a lever arm 30 pivoted to the holder as at 31 and 80 carrying a weight 33 which may be held at any adjusted position by set screw 34. Connection between the lever arm 30 and the upper tube member is here shown as a screw-eye 36 embracing the lever arm and threaded into the upper member 23.

The nipper steels 40 and 44 are triangular in cross section and each has a semi-cone shaped bore 41 cooperating with the similar bore in the opposed face of the other. It 90 has been found preferable to adjust the lower steel so that its upper face shall be approximately a sixteenth of an inch more or less below the horizontal center line of the yarn so that the horizontal shallow 95 groove 46 in the rear point of the upper nipper steel shall be in approximately such center line. A small bore 47 leads to the apex of the conical enlargement in the face of the upper steel and receives the central 100 fibers, or as here described, the marker which is to be placed centrally in the yarn, through the rear conical enlargement 49. The bell 20 is slotted as at 50 to facilitate 105 the threading of the marker into the tube.

The upper nipper steel 40 is provided with a relatively heavy lead casting 52 of the proper weight, depending somewhat upon the character of the fiber, to spread the sliver and to keep it from twisting at the 110

center until the marker enters. By lowering the lower nipper steel as stated the marker is fed in the proper place while the sliver is spread and the spread edges begin to twist around the marker. The set screw 53 is adjusted and locked in place by a lock washer in the obvious manner.

In operation the initial twist is imparted to the sliver as it leaves the steels in a somewhat spread and flattened condition and owing to the pointed shape of these steels the edges of the sliver begin to twist or curl around the center at the point where the center is fed in with the result that the center is enclosed in a complete fiber covering. The twisting is completed in the rear end of the channel in the jaws and the twisted yarn is smoothed and finished in its passage through and out of the front end of the jaws.

What I claim is:

1. In a spinning jenny nipper, a nipper tube, a plurality of nipper steels in said tube, and means for feeding a center member in proximity to the apex of said steels and for guiding a sliver around said member.
2. In a spinning jenny nipper, a nipper tube, a lower steel and an upper steel having a sliver receiving opening and also having a center member receiving and guiding opening arranged at an angle to the sliver receiving opening and communicating therewith.
3. In a spinning jenny nipper, a nipper tube, a lower nipper steel and an upper nipper steel formed with a conical sliver receiving recess in the proximate faces, one of said steels also having a center member receiving and guiding opening communicating with the conical recess in proximity to its apex.

4. In a spinning jenny nipper, a nipper tube, an adjustable pointed lower nipper steel and a weighted pointed upper nipper steel with a conical sliver receiving recess in the proximate faces of the steels, the apex of the recess being in proximity to the points, one of said steels also having a center member receiving and guiding opening communicating with the conical recess in proximity to its apex.

5. In a spinning jenny nipper, a nipper tube, a lower nipper steel and an upper nipper steel, the upper steel being characterized by the provision of a groove in its point, said groove merging with the sliver receiving opening in the upper steel and being closed on the lower side to form a channel by the upper face of said lower steel, and means for feeding a center member to said groove.

6. An upper nipper steel for a spinning jenny nipper, characterized by the provision of a semi-conical sliver receiving opening in the rear and bottom faces of the steel, a marker receiving hole at an angle to the bounding surface of the sliver opening, and a groove in the lower face of the steel communicating with the marker bore and with the apex of said sliver receiving opening.

7. The method of inserting a central member in a yarn which consists in spreading a sliver in a plane to one side of the axis of twist, depositing a central member on said spread sliver and in the axis of twist, and in twisting said sliver about said central member at the point where the central member is fed to the sliver while holding said sliver in firm contact with the central member at such point but with its edges free transversely of said point.

JOHN JOSEPH KINNEY.
